ABSTRACT

Composition for prevention of ferrous corrosion consisting essentially of (a) sorbitol, (b) benzotriazole or tolyltriazole, and (c) a water-soluble phosphate.

11 Claims, No Drawings

ANTI-CORROSION COMPOSITION

The present invention relates to novel and improved corrosion inhibiting compositions and methods of inhibiting corrosion. The invention provides corrosion protection for metal parts such as heat exchangers, engine jackets, pipes and prevents metal loss, pitting and tuberculation of iron base alloys which are in contact with water.

The invention is directed to a relatively non-toxic, non-chromate, non-zinc corrosion inhibiting composition which is capable of protecting ferrous metals from the corrosion, said composition consisting essentially of (a) sorbitol, (b) benzotriazole or tolyltriazole, and (c) water-soluble phosphates, e.g., phosphoric acid, disodium phosphate, sodium tripolyphosphate, or tetrapotassium pyrophosphate. This mixture can be blended with any well known scale inhibitors or dispersants. The prior art teaches the use of benzotriazole and water soluble phosphate as corrosion inhibitors for aqueous systems. But the protection offered for ferrous metals with this composition is not beyond criticism. We have now discovered that the addition of sorbitol to such a composition significantly improves the protection of ferrous metals in aqueous systems. Typical industrial applications where the instant invention is useful include water treatment, acid pickling, radiator coolant, hydraulic liquid, anti-freeze, heat transfer medium, and petroleum well treatment.

TEST PROCEDURE AND EXAMPLES

In these tests, circulating water having the following composition was used.

Calcium sulfate dihydrate	714 ppm
Magnesium sulfate heptahydrate	519 ppm
Sodium bicarbonate	185 ppm
Sodium chloride	989 ppm

During the tests, the circulating water was fed to a closed circulating test system at a rate of 5 gallons per day, the overflow from the test system being discharged to waste.

In the closed circulating system, circulating water having a temperature of 130° F. and a pH of 7.0-8.0 was fed at a rate of one gallon per minute to a coupon chamber containing test coupons for the corrosion test. The total circulating time for each test was 10 days.

Mild steel, brass (33 wt. percent zinc), and copper coupons having an average area of 26.2 cm.² were used in the test chamber. The coupons were carefully cleaned and weighed before use. The components stated below were added to the circulating water at the levels indicated, for each of the tests, as stated. Following the tests, each coupon was cleaned with inhibited hydrochloric acid, rinsed, dried and weighed to determine the corrosion rate in mils per year.

The results obtained are shown in the following Table.

Exam- ple	Test Conditions	Cooling Water System, pH 7-7.5, 130° F., 10 days		
		Corrosion Rate in Mils per year		
	Addition (ppm)	Steel	Copper	Brass
1	Blank (no treatment)	19.6	1.1	1.7

Exam- ple	Test Conditions	Cooling Water System, pH 7-7.5, 130° F., 10 days		
		Corrosion Rate in Mils per year		
	Addition (ppm)	Steel	Copper	Brass
2	BT 2 ppm	20.0	0.2	0.2
3	BT 10 ppm	19.2	0.2	0.2
4	H ₃ PO ₄ 4 ppm	20.0	0.56	0.36
10	5 Sorbitol 5	20.0	0.8	0.3
6	BT 3 ppm + Sorbitol 5 ppm	14.9	1.8	0.6
7	BT 3 ppm + phosphoric acid 4 ppm	10.1	0.5	1
8	Sorbitol 5 ppm + H ₃ PO ₄	9.4	1.5	0.6
15	ppm			
9	Sorbitol + H ₃ PO ₄ + BT 5 4 3	2.8	0.5	0.6
10	Sorbitol + H ₃ PO ₄ + BT 5 4 3	3	0.6	0.2
11	Sorbitol + H ₃ PO ₄ + BT 6 4 3	2.7	0.25	0.3
20				

Preferred formulations are as follows:

Ex. 12	Liquid Formulation
	Deionized water
	Phosphoric acid (75%)
	Ethane-1-hydroxy-1,1-diphosphonic acid (40%)
	Sorbitol
	Potassium hydroxide (45%)
	Tolytriazole
	100.0%

Ex. 13	Powder Formulation
	Sodium phosphate (Mono basic)
	Monohydrate
	Ethane-1-hydroxy-1,1-diphosphonic acid
	Benzotriazole
	Sorbitol
	Sodium sulfate
	Sodium carbonate
	100.0%

45 In the composition, the preferred weight ratio of sorbitol:benzotriazole or tolyltriazole:water-soluble phosphate is 0.01 to 100:0.01 to 100:1. Even more preferably it is 0.1 to 10:0.1 to 10:1. These same ratios are 50 applicable to levels of the compounds in water, where the phosphate is preferably maintained at about 0.01 to 5000 ppm, and even more preferably about 0.1 to 50 ppm.

We claim:

1. Composition consisting essentially of
  - (A) sorbitol;
  - (B) a member selected from the group consisting of benzotriazole and tolyltriazole; and
  - (C) a water-soluble phosphate.
2. Composition according to claim 1 in which the weight ratio of A:B:C is about 0.01 to 100 : 0.01 to 100 :1.
3. Composition according to claim 2 in which the weight ratio of A:B:C is about 0.1 to 10 : 0.1 to 10 :1.
4. Composition according to claim 1 in which the group member is benzotriazole.
5. Composition according to claim 1 in which the group member is tolyltriazole.

6. Composition according to claim 4, consisting essentially of

Sodium phosphate (Mono basic)	5
Monohydrate	15.84%
Ethane-1-hydroxy-1,1-diphosphonic Acid	8.04%
Benzotriazole	9.00%
Sorbitol	15.00%
Sodium sulfate	36.47%
Sodium carbonate	15.65%

7. Composition according to claim 5, consisting essentially of

Deionized water	12.8%	15
Phosphoric acid (75%)	10.0%	
Ethane-1-hydroxy-1,1-diphosphonic		20

-continued

acid (40%)	15.0%
Sorbitol	10.0%
Potassium hydroxide (45%)	46.2%
Tolytriazole	6.0%

8. Process of inhibiting ferrous corrosion in an aqueous system comprising maintaining therein (A) sorbitol; (B) a member selected from the group consisting of benzotriazole and tolyltriazole; and (C) a water-soluble phosphate, wherein the weight ratio of the components A:B:C is 0.01 to 100 : 0.01 to 100 : 1, and component C is maintained at about 0.01 to 5000 ppm.

9. Process according to claim 8 in which the group member is benzotriazole.

10. Process according to claim 8 in which the group member is tolyltriazole.

11. Process according to claim 8 in which the A:B:C ratio is 0.1 to 10 : 0.1 to 10 : 1.
